UNITED STATES PATENT OFFICE

173,094

CASSEROLE

Viktor Schreckengost, Cleveland, Ohio, assignor to The Consolidated Iron-Steel Mfg. Co., Cleveland, Ohio, a corporation of Ohio

Application October 7, 1953, Serial No. 27,104

Term of patent 3½ years

(Cl. D44—1)

To all whom it may concern:

Be it known that I, Viktor Schreckengost, a citizen of the United States and a resident of Cleveland, Cuyahoga County, Ohio, have invented a new, original, and ornamental Design for a Casserole, of which the following is a specification, reference being had to the accompanying drawing, forming a part hereof, in which:

Fig. 1 is a perspective view of a casserole showing my new design;

Fig. 2 is a side elevational view thereof;

Fig. 3 is a bottom plan view thereof.

I claim:

The ornamental design for a casserole, as shown.
